UNITED STATES PATENT OFFICE.

DUNCAN C. McCaig, OF VANCOUVER, BRITISH COLUMBIA, CANADA.

CRUDE-OIL ATOMIZER AND AIR-MIXER.

1,255,449.

Specification of Letters Patent.

Patented Feb. 5, 1918.

Application filed February 27, 1917. Serial No. 151,836.

To all whom it may concern:

Be it known that I, DUNCAN C. McCaig, a citizen of the Dominion of Canada, residing at Vancouver, in the Province of British Columbia, Canada, have invented certain new and useful Improvements in Crude-Oil Atomizers and Air-Mixers, of which the following is a specification.

This invention relates to a crude oil burner wherein the oil is atomized and thoroughly mixed with the required air for combustion before delivery to the burner outlet. This is accomplished by delivery of the oil as required onto the vanes of a small centrifugal fan by which the air is drawn in and delivered to the burner, the fan being driven at a high speed of rotation by an independent motor, preferably a turbine driven by a jet of water from the domestic water service.

20 The invention is particularly described in the following specification, reference being made to the drawings by which it is accompanied, in which:

Figure 1 is a section across the axis of the air fan on the plane 1—1 in Fig. 2 and in the direction indicated by the arrows.

Fig. 2 is a section of the same on the line 2—2 of Fig. 1 looking in the direction indicated.

30 Fig. 3 is a modified form of air vane for the fan, and.

Fig. 4 is a view of the water turbine by which the air fan is operated, a part of the casing being removed.

35 In these drawings 2 represents a centrifugal air fan rotatable within a casing 3, air being admitted at 4 adjacent the center and delivered through the outlet 5 to the pipe 6 which forms the burner.

40 The shaft 7 on which the fan 2 is secured is directly driven at a high rate of speed by any suitable motor, and the oil is delivered through a small aperture 14 onto the blades of the fan, and is finely atomized and mixed with the air drawn in and expelled by the fan blades. The oil may be delivered by gravity or may be sprayed under pressure and to assist the breaking up of the oil the outer edges of the fan blades may be serrated, as shown in Fig. 3. The amount of air admitted may be regulated to the requirements of the oil delivery by an apertured valve plate 15 rotatable over the inlet apertures 4 to the fan, and held up to its face by a light spring. This plate may have

a handle by which air admission may be more easily regulated.

Although the centrifugal fan may, as stated, be driven by any suitable motor, the drawings show a convenient application for domestic use. In it a water turbine 8 is secured on the fan shaft 7 and is rotatable within a casing 9 secured to and corresponding with the casing 3 of the fan, a partition 10 being introduced in the casing joint to 65 separate the turbine casing from the fan casing. On the periphery of this turbine a fine jet of water under pressure is delivered at 11, which water is derived from the domestic water service connected to it at 12 and the 70 water is drained from the casing through the outlet 13.

So constructed, a particularly simple and effective burner is provided. The oil, as it drops through the aperture onto the vanes 75 of the fan, is, owing to the high speed of the fan blades, thoroughly broken up and finely atomized and becomes well mixed with the air before delivery to the burner, and the amount of air may be regulated to the exact 80 requirements of combustion. Means may be provided for heating the air and the oil before delivery to the fan or for heating the mixed air and oil before delivery to the burner outlet, but such has not been found 85 necessary in the smaller burner tried.

Although described and illustrated as for the atomization of heavy oil and the mixing of it with the air required for its combustion, the device is also applicable to a finely 90 divided fuel, such as coal dust or the like.

Having now particularly described my invention, I hereby declare that what I claim as new and desire to be protected by Letters Patent is:

1. A fuel atomizer and air mixer, comprising the combination with a burner tube, of a centrifugal air fan delivering a supply of air to that tube, the ends of the blades of said fan being serrated, means for delivering the fuel for combustion directly onto the blades of the fan above the axis of rotation, and means for driving the fan by a motor directly connected to the fan shaft.

2. A fuel atomizer and air mixer, comprising the combination with a burner tube, of a centrifugal air fan delivering a supply of air to that tube, means for delivering the fuel for combustion directly onto the blades of the fan above the axis of rotation, a light

turbine secured on the fan shaft and rotatable within a casing secured to the casing of the fan and separated therefrom by a partition, and means for delivering a jet of water 5 under pressure onto the vanes of the turbine.

3. A fuel atomizer and air mixer, comprising a casing having a central partition dividing the same into two chambers, a centrifugal fan located in one of said chambers, 10 a turbine wheel located in the other chamber, a common axis for said wheel and fan located eccentrically with relation to the axis of said chambers, means for admitting

a jet of fluid tangentially into the turbine chamber to drive the turbine wheel, a burner 15 outlet duct from said fan chamber through which the products in the fan chamber are delivered, valved air induction ports for said fan chamber arranged concentrically with relation to the axis of said fan, and an oil 20 dropping duct for dropping oil onto the rotating fan blades at the top of the fan chamber, substantially as shown and described.

In testimony whereof I affix my signature. 25
DUNCAN C. McCAG.
